UNITED STATES PATENT OFFICE.

AUGUST H. PETERSEN, OF NEW YORK, N. Y.

GRINDING OR PULVERIZING MACHINE.

942,865

Specification of Letters Patent. Patented Dec. 7, 1909.

Application filed March 17, 1909. Serial No. 484,025.

To all whom it may concern:

Be it known that I, AUGUST H. PETERSEN, a citizen of the United States, and a resident of the borough of Brooklyn, in the city and State of New York, have invented certain new and useful Improvements in Grinding or Pulverizing Machines, of which the following is a specification.

My invention relates to means for grinding, disintegrating or pulverizing various substances, as for instance rubber, so that the same may be reduced to a finely granular state and be better adapted for such subsequent treatment or manipulation as may be desired.

The invention consists in the novel construction, arrangement and combination of various devices and parts as hereinafter more particularly described.

In the accompanying drawings Figure 1 is a top or plan view of an apparatus constructed according to my invention; Fig. 2 is a transverse vertical section taken on the line 2—2 of Fig. 1; Fig. 3 is a transverse vertical section of a portion of the apparatus taken on the line 3—3 of Fig. 1; Fig. 4 is a horizontal section taken on the line 4—4 of Fig. 3; and Fig. 5 is a view of the invention comprising a tank for holding a solvent as hereinafter described.

In carrying my invention into effect I provide a suitable frame 7, mounted on legs 20, which are securely attached in some adequate manner to a base or foundation 8. Suitably journaled in the frame 7 are shafts 9 and 10, each of which bears a crushing cylinder or roller, which are designated respectively 11 and 12. The roller 11 is shown provided with longitudinal grooves 21, but these are not essential to the invention. The shaft 9 is provided at one end with a large gear wheel 13 rigidly attached thereto and at the other end with a smaller gear wheel 14 which gears with a corresponding gear wheel 15 on the shaft 10. Below the large gear wheel 13 is a driving gear wheel 16 which communicates power to the wheel 13 and by means of which the two shafts and the two crushing rollers are driven. This driving gear wheel 16 is loose on its shaft 17 and motion is communicated to it by means of the clutch 18 which is fast on the shaft 17. Power may be communicated to this shaft 17 by pulley and belt, or in any desired manner.

Inside of the frame 7, and on each side

thereof, a short distance below the ends of the cylinders 11 and 12, are secured brackets 30, and extending across from the ends of these brackets 30 are transverse members 31, 60 the whole forming a rectangular frame below the cylinders. Secured to this frame, and extending across the space between same and the cylinders, are plates 32, curved upward as shown in Fig. 2 so as to follow approximately the curve of the cylinders, and having their adjacent upper edges rigidly secured together. To the lower or outer edges of the plates 32 are hinged other plates 33, also curved to conform to the 70 curve of the cylinders, and of sufficient size to reach approximately half-way around the same and up to a point about over the highest part. To the upper edges of these plates 33 are secured straps 34, and when the plates 75 33 are hinged up into the position shown in Fig. 2, these straps 34 extend over the tops of the cylinders and meet at or near the middle point (see Fig. 1) and may then be secured together by bolts 35 (see Figs. 1 and 2). The plates 33 are provided with perforations 36 near their lower edges. One of the plates 33, as for instance the one shown on the right in Fig. 2, may be provided with bolts 37 which engage with sockets in the 80 frame 7. The plates 32 and also the plates 33 are provided with flanges, shown more particularly in Fig. 3 of the drawings, and designated respectively 38 and 39. These flanges extend inwardly a short distance 90 along and contiguous or nearly so with the ends of the cylinders 11 and 12.

On each side of the machine, and bolted or otherwise rigidly secured to the top of the frame 7, is a plate 40, having strengthening 95 ribs 41 and a laterally projecting lug 42. Inside of each of these plates 40 is a movable plate 43, which is supported by a screw 44 which passes through said lug 42 and is thereby vertically adjustable. Secured to 100 the inner and upper corners of each of these plates 43 are guides or deflectors 45. The plates 43 extend downward and are of such a shape as to extend partly down between the cylinders 11 and 12, as best shown in 105 Fig. 3, and the deflectors 45 also extend down so as to nearly contact with the surface of the cylinders.

The cylinders 11 and 12 are hollow, and the shafts 9 and 10 upon which they are mounted are perforated so as to communicate with the hollow interior of the cylin-

ders. Steam pipes 50 extend into the opening at the end of these tubular shafts, suitable bushings or packings being provided to prevent undue leakage of steam. When the machine is in use, steam may be admitted through said pipes 50 into the hollow space in the interior of the cylinders 11 and 12. An escape cock, not shown in the drawings, is provided to allow the water of condensation to be drawn off when desired. A pan or tray 55 is provided, located beneath the cylinders, and supported on rods 56 extending across between the legs 20.

In Fig. 5 I show a form of my invention which I employ when it is desired, in addition to the reduction of the material to a pulverized form, to make a solution of the same. In this form of the apparatus I provide a vessel or tank 75, adapted to contain any desired solvent or menstruum; which tank entirely surrounds and incloses the parts heretofore described which co-operate in the grinding of the material. The shafts and other parts which extend out through the walls of the tank or vessel 75 are of course provided with bushings or packings or made liquid-tight in some suitable manner. The tank is also provided with lids or covers 76, attached by hinges 77 or in any other suitable manner, which may be closed after the solvent has been placed into the tank and before the operation of the machine is commenced. In Fig. 5 I have also shown additional shields or guards 80 analogous to the shields 33. These shields 80 may be introduced after the machine is charged, being adapted to confine the material being ground and prevent its rising up away from the tops of the grinding cylinders.

The operation of my invention is as follows: The material, as for instance vulcanized rubber scrap, being torn or broken into fragments of proper size, is introduced into the top of the machine, between the cylinders 11 and 12, which are rotated by the gearing connected therewith so as to draw the rubber down between them. These cylinders are practically in contact, and as the rubber passes down between them it is crushed into particles more or less fine, and falls down upon the curved plates beneath the cylinders, being carried around upon said plates by the friction of the cylinders and the pressure of the following material. As the material becomes pulverized, as it successively passes the perforations 36 in the plates, such pieces as are small enough drop through into the tray 55, while the larger pieces are carried around and pass again and again between the cylinders, the operation being repeated until all of the pieces are small enough to pass through the perforations 36 into the pan or tray 50. The flanges 38 and 39, and the plate 43, prevent the escape of the frag-

ments of material off of the ends of the cylinders, and the deflectors 45 guide toward the middle such of the fragments as may be too near the ends, as the same pass up over the cylinder and are about to again descend between the two cylinders. During the operation of the machine the cylinders may, if the nature of the material requires, be kept heated by steam introduced into their hollow interiors, or in some cases it may be well to cool the same. When a sufficient quantity of pulverized material has passed down into the pan or tray it may be removed, emptied and replaced. A cover or slide may be provided below the perforations, which may be kept in place at the first part of the operation of the machine and removed when the material is partly pulverized so that a portion of the same is small enough to pass through the perforations.

Having thus described my invention, what I claim as new and desire to secure by Letters Patent is as follows:

1. In a grinding or pulverizing machine, the combination with grinding cylinders or rollers and means adapted to operate the same, of a shield or casing partially surrounding each roller having a smooth inner surface and adapted to receive the material being ground after it has passed between the rollers and to guide said material and permit it to be carried around by said rollers and passed again between the same.

2. In a grinding or pulverizing machine, the combination with grinding cylinders or rollers and means adapted to operate the same, of a shield or casing partially surrounding each roller and provided with perforations, said shields being adapted to receive the material being ground, after it has passed between the rollers, to permit the pulverized portion of such material to pass through said perforations and to permit the remainder of the material to be carried around by said rollers and passed again between the same.

3. In a grinding or pulverizing machine, the combination with grinding cylinders or rollers and means adapted to operate the same, of a shield or casing partially surrounding each roller and provided with an inturned end flange adjacent to the ends of the rollers and also provided with perforations, said shields being adapted to receive the material being ground, after it has passed between the rollers, to permit the pulverized portion of such material to pass through said perforations and to permit the remainder of the material to be carried around by said rollers and passed again between the same.

4. In a grinding or pulverizing machine, the combination with grinding cylinders or rollers and means adapted to operate the same, of a shield or casing, composed of a

plurality of sections, pivotally united to each other, partially surrounding each roller and provided with an inturned end flange adjacent to the ends of the rollers and also 5 provided with perforations, said shields being adapted to receive the material being ground, after it has passed between the rollers, to permit the pulverized portion of such material to pass through said perforations 10 and to permit the remainder of the material to be carried around by said rollers and passed again between the same.

5. In a grinding or pulverizing machine, the combination with grinding cylinders or 15 rollers, means adapted to operate the same, and means adapted to direct the material to be ground toward the middle part of the rollers and away from the ends thereof, of a shield or casing partially surrounding each 20 roller and provided with an inturned end flange adjacent to the ends of the rollers and also provided with perforations, said shields being adapted to receive the material being ground, after it has passed between 25 the rollers, to permit the pulverized portion of such material to pass through said perforations and to permit the remainder of the material to be carried around by said rollers and passed again between the same.

mainder of the material to be carried around by said rollers and passed again between the same.

30

6. In a grinding or pulverizing machine, the combination with grinding cylinders or rollers, means adapted to operate the same, and means adapted to direct the material to be ground toward the middle part of the 35 rollers and away from the ends thereof, of a shield or casing partially surrounding each roller composed of a plurality of sections pivotally united and provided with means adapted to hold same in position adjacent to 40 the roller, and provided with an inturned end flange adjacent to the ends of the rollers and also provided with perforations, said shields being adapted to receive the material being ground, after it has passed between 45 the rollers, to permit the pulverized portion of such material to pass through said perforations and to permit the remainder of the material to be carried around by said rollers and passed again between the same.

AUGUST H. PETERSEN.
